UNITED STATES PATENT OFFICE

JOHN GOOD, OF GARDEN CITY, NEW YORK, ASSIGNOR TO GOOD INVENTIONS CO., OF NEW YORK, N. Y., A CORPORATION OF NEW YORK

OIL BURNER

Application filed July 27, 1926. Serial No. 125,138.

The invention relates to so-called house heating burners although useful in other relations and its objects are to improve the reliability of operation, eliminate danger of explosion and generally to reduce the number of parts and simplify the construction of this class of apparatus.

In the drawings:

Fig. 1 is a side elevation of a burner, partly in section, incorporating the principles of this invention.

Fig. 2, a horizontal plan view of the fire pot thereof on the line II—II.

Fig. 3 is an enlarged scale view of the parts of Fig. 1, in the burning position.

Figs. 4 and 5 are respectively sections on the lines IV—IV and line V—V of Fig. 3, and

Fig. 6 is a diagram of the system.

20 The burner comprises a combustion chamber or fire pot 1 of any desired type adapted to be supported inside the combustion space of an ordinary furnace represented at 2 and connected to or mounted on the end of an air casing 3, which extends outside the furnace, being usually provided with legs to rest on the floor, as indicated. The use of a fire pot such as 1 is preferred but is not essential; the flame can, if desired, be projected directly into the combustion space of the furnace or be applied in any other way according to circumstances.

Combustion supporting air is supplied to the fire pot, or to the combustion space of the furnace, through the air casing, by an electric motor 4 driving a fan blower 5 which is mounted on the outer end of the casing. The air enters the fire pot or combustion space through the openings 6 (Fig. 2) in the end casting 7 at either side of the fuel spray device. The motor also drives a small pump 8 which atomizes the fuel, preferably by means of air pressure, in which case the pump is an air pump, and in this case, the suction side of this pump is connected to a vacuum-feed tank 9, suitably elevated, which draws in fuel from a remote source not shown and delivers it to the burner by gravity. The cabinet 10, which

may be mounted on the air casing 3, as shown, houses certain electromagnetic and thermal control mechanism presently referred to, and all the rest of the operating mechanism is mounted on a tray 11 in the air casing 3, which can be withdrawn endwise therefrom, like a drawer, for inspection purposes.

55 Liquid fuel from the elevated tank 9 flows therefrom, by fuel pipe 12, through a shut off valve 13, oil strainer 14, oil pipe 15, to the oil receptacle 16 of an electromagnetic oil valve 17, and thence through a regulating valve 18 and fuel line 19 to the spray nozzle 20, or to whatever type of fuel discharge mechanism is preferred to be employed. The oil is supplied to the sprayer by gravity from the tank 9, which as stated is operated by the pump 8. The oil supply is thus motor-operated. The electric fuel valve 17 is known to the art; it comprises a valve proper opened by the pull of an electromagnet 21, bridged across the circuit of the driving motor 4 as indicated in Fig. 6, so that the valve is open whenever the motor is active. The regulating valve 18 controls the rate of oil delivery to the sprayer, being located between valve 17 and the spray nozzle, but arranged so that it can be operated from outside the casing without withdrawing the tray. In this position it can be adjusted to control the flame without the objectionable puff commonly incident to the starting of combustion in oil-heating apparatus. The nozzle 20 is mounted on the igniter housing 22, which is carried on the tray 11, where it projects into and occupies a central opening 23 in the front wall casting 7.

60 Air is delivered from the pump 8 through pipe 24, chamber 25 and air line 26 to the nozzle. It is preferred to atomize the fuel and introduce it into the fire pot by air pressure but, as already mentioned, the broader principles of the present invention are independent of the method of introducing the fuel and accordingly there is no intention to limit the claims to the use of spraying air, except as otherwise specified.

65 The igniter is preferably an electric re-

sistance wire 27, coiled on a refractory base and furnished with screw shell and center contact terminals like an ordinary Edison-base electric lamp, by means of which it is physically supported on, and electrically connected to and through, the igniter carriage 28 with the wire conductors in a flexible electric cable 29, the latter forming part of the igniter circuit referred to below.

10 The igniter has two positions, being movable from its igniting position immediately below the sprayer, as shown in Figure 1, to a position rearward thereof as shown in Figure 3, and for this purpose the igniter carriage 28 is mounted to slide on two parallel rods 30 fixed by their ends in the igniter housing 22, see Figure 2. The carriage is moved by a connecting rod 31 and a lever 32, which latter is connected to a motor device, in the present case pneumatically operated and constituted of a collapsible or sylphon bellows 33 contained in an air chest 34. Some of the high pressure air from the air line 26 is admitted to this chest through a T connection having a restricted opening 35 (Figure 3). When the bellows is collapsed by the air pressure the igniter is withdrawn from the fire pot to the position shown in Figure 3. It will be apparent that the igniter carriage 28 can be movably mounted in various other ways and can be moved by motor devices different from that shown but which will operate to withdraw the igniter in like manner coincidentally with the transmission of high pressure air to the sprayer. This occurs at or slightly after the beginning of the fuel delivery produced by the air pressure.

In the forward position of the igniter 40 a finger 36 (Fig. 5) mounted on the motor lever 32 closes the igniter switch 37, which is mounted on the air chest and the circuit of which is indicated in Figure 6 and described below. It will be noted that this 45 switch is closed only when the igniter is advanced to its igniting position, and that this is also the shut down or standby position of the burner. The sylphon bellows 33 has a coil spring enclosed within it or 50 otherwise acting on it for moving the carriage to its igniting position; the air pressure holds the igniter in its retracted position against this spring, and thus so long as the spraying air is flowing to the sprayer, 55 that is to say, so long as fuel is being delivered for normal combustion, the igniter is withdrawn into its housing as in Figure 3.

60 The electric connections between the control mechanism in the cabinet 10 and the electrical members in the casing 3 are made separable, as indicated at 38, so that they can be disconnected when the tray 11 is to 65 be withdrawn; some of the wires inside the

casing are protected and supported by guard tubing indicated at 40.

The diagram of Figure 1 indicates that the room thermostat 41 and the house supply circuit are used for controlling the burner through the apparatus contained in the cabinet 10. This apparatus comprises two magnetic switches diagrammatically shown and marked 42 and 43 respectively in Figure 6, a thermostatic member 44 herein referred to as the lag thermostat, an electric resistance heater 49 therefor, and, in the case of alternating current supply, a transformer indicated at 45. The circuit connections of these parts are not substantially different from the system shown and claimed in the application of John Good and Edgar H. Olsen, Serial No. 42,147, filed July 8, 1925, to which reference may be had.

The operation is as follows, assuming that the burner has been inactive for a period of time and its parts are cold. At such time the igniter mechanism will be in the standby position indicated in Figure 1, the igniter switch 37 being closed, because the carriage 90 is advanced, but no current is furnished to the igniter at this time. If now the room thermostat 41 calls for heat by closing against its two contacts 46 and 47, (particularly 47), it will establish a closed circuit, 95 which includes the transformer 45, the magnet 42, the (closed) igniter switch 37, the lag thermostat 44, the room thermostat 41, and nothing else. Energization of magnet 42 closes the circuit marked "Ignition circuit" which derives its power from the high voltage side of the transformer and includes the igniter resistance wire 27 and the resistance heater 49 in series. This resistance 100 is mounted in heating relation to the lag thermostat 44, being generally wound about the latter although not so shown in the diagram. The heating of the lag thermostat thus begins coincidently with the energization of the igniter and the two are mutually dependent, being in series. The heating of the thermostat 44 bends the latter toward the right but requires several moments to complete its movement. The magnet 42, when energized by the action of the room thermostat, has also closed and connected the two contacts 50 and 51. This has no immediate effect. It has also closed the pair of contacts 53, the effect of which is merely to establish a holding circuit for the magnet 105 itself, so that it will remain energized even after the lag thermostat has separated from its lefthand or "cold" contact 54. This holding circuit, if traced, will be seen to include the magnet 42 and igniter switch 37, 110 in series relation, so that the opening of the latter will deenergize that magnet as later described.

While the lag heater 49 is getting hot the igniter 27 is also becoming incandescent,

being still in its advanced position and directly below the fuel discharge device 20. No other effect occurs until the lag thermostat 44, becoming sufficiently heated, closes 5 against contact 55. When it engages this contact it establishes a circuit which, starting from the lower side of the transformer, is traced as follows: the magnet 43, contacts 50 and 51, (connected by action of magnet 10 42) contact 55, lag thermostat 44, wire 56 and room thermostat contacts 47 and 46 back to the transformer. This energizes the magnet 43. The closure of the lag thermostat against contact 57, thereby connecting 15 the latter with 55, has no effect except to insure the energization of magnet 43 in the event of any failure or weakness of contact at 47 in the room thermostat; this being the last made of the two contacts in 20 that device, is sometimes not made with a sufficiently firm pressure. The energization of magnet 43 closes the "motor circuit" connected, as indicated, on the high voltage side of the transformer and it also connects 25 contacts 58 which closes the holding circuit for that magnet shown by heavy lines. This insures that the magnet 43 will remain energized for as long as the thermostat 41 continues to call for heat by its engagement 30 with contact 46. The motor circuit includes the electric oil valve 17 above referred to, but it will be noted that the motor circuit can not close until sufficient time has elapsed for the lag thermostat 44 to move from its 35 "cold" or left-hand position to its "hot" or right-hand position, and this time is sufficient to allow the igniter 27 to attain an igniting temperature and for any residuary explosive vapor in the combustion space to become dissipated. The first effect of the closure of 40 the motor circuit is to open the electric valve 17, such valve being relatively quick-acting and quicker to respond to the current than the motor 4. Opening of the oil valve 45 17 causes an instantaneous and slight spurt of oil to be delivered from the spray nozzle 20, without air, which drips on to the now incandescent igniter. The quantity delivered is small enough so that it does not flood 50 or chill the igniter, but is instantly inflamed and begins to burn. The actual ignition of the fuel is thus of non-atomized oil, and this is preferred though not essential to successful operation; the atomized spray will 55 also ignite from the igniter. The preliminary drip of oil on the projecting igniter is promptly followed by the beginning of the normal fuel spray produced by the high pressure air arriving from the air pump 8 and is accompanied by the normal delivery 60 of lower pressure air from the fan blower 5. The delay in the commencement of the normal spray is due in part to the capacity of the air receiver 25 in the air line and the time required for the motor to attain its 65 speed. As the pressure builds up in the air line, it is also gradually transmitted through the restricted passage 35 into the pneumatic motor device 34. This compresses the bellows and withdraws the igniter into its 70 housing 22, simultaneously opening the switch 37, the effect of which is to break the holding circuit of magnet 42, de-energizing the latter and thereby opening the "ignition circuit". Thereupon the igniter itself 75 and the lag heater 49 in the cabinet 10 cool down to normal temperature and the lag thermostat 44, on cooling, restores itself to its normal "cold" side position engaging contact 54 ready for the next cycle. The 80 burner is now in normal combustion operation which will cease whenever the heavy line circuit is broken in the room thermostat. Various safeguards will be observed to be 85 present in the circuit arrangement above described but which need not be here described in detail. It is impossible, for example, to re-energize the magnet 43, after its circuit has been opened, until the lag thermostat has again moved into connection 90 with its hot side contact 55. This enforces an appreciable interval, as above stated, and thereby avoids a serious objection to many proposed burner systems, in that it is not possible to recommence the delivery of fuel 95 into a fire pot still remaining at an igniting temperature from its last preceding operation. In the present system, this danger of mishap is avoided because the igniter must be in readiness not only to receive but also 100 to ignite the fuel, before the motor-operated fuel discharge device is even set in operation. Ignition is facilitated by the fact that when the igniter carriage 48 is in its projecting or forward position, it closes the 105 passageway through the igniter housing so that no substantial air draft can pass over the igniter while it is active, and even though there may be a considerable flow of air on either side of it through the side 110 passages 6. When the carriage withdraws, air may flow through the igniter housing and is effective for burning off any residue of oil on the igniter, keeping it clean and also cooling it, so that its useful life will be 115 prolonged.

The following is claimed:—

1. An oil burner comprising means for delivering oil initially in non-spray form for ignition and subsequently in spray form for normal combustion, a movable igniter positioned to receive and ignite the initial delivery, and means operative thereafter to withdraw the igniter from igniting position. 120
2. An oil burner comprising oil delivery means adapted to deliver oil initially in non-spray form for ignition and subsequently in spray form for normal combustion, an igniter positioned to receive and ignite the initial delivery and means for effecting such 125 relative movement of the oil delivery and

- the igniter that subsequent to ignition the latter is outside the sprayed delivery zone.
3. An oil burner comprising a fuel delivery passage terminating in a discharge outlet to the burner, means adapted to deliver oil at said outlet initially in non-spray form, an igniter positioned below and in the path of such delivery adapted to ignite the same and means operative there-
10 after to deliver the fuel at said outlet in spray form, for normal combustion.
4. An oil burner comprising an oil spray nozzle, means for discharging oil therefrom initially under low pressure, to effect non-spray delivery, and subsequently under higher pressure, to effect delivery of the oil in spray form, and an igniter positioned to receive and ignite said initial non-spray delivery of oil.
- 20 5. In an oil burner, the combination of a fire pot and an air casing leading thereto, a drawer insertable in said casing up to the pot, a movable carriage mounted on the drawer, an igniter on said carriage and means for moving the igniter beyond the end of the drawer into the fire pot.
6. In an oil burner, the combination with the combustion chamber of an air casing leading thereto, a drawer in said casing, an igniter and a movable carriage therefor mounted on the drawer, a motor device on the drawer for moving the carriage and elec-
30 trical and fuel supply connections at the end of the drawer.
- 35 7. In an oil burner, the combination with the combustion chamber of an air casing leading thereto, a drawer in said casing, a carriage and an igniter thereon mounted on the drawer and movable longitudinally of the casing into and out of the combustion space, a motor on the drawer for moving the carriage, and electrical and fuel supply connections outside the drawer on the end of the same remote from the combustion space.
- 40 8. In an oil burner, the combination with the combustion chamber of an air casing leading thereto, a drawer in said casing, a carriage mounted on the drawer and movable longitudinally of the casing toward
45 and from the combustion space, a motor on the drawer for moving the carriage, a fuel nozzle on the drawer located to discharge into the combustion space and an igniter on the carriage adapted to be moved thereby
50 into and out of the combustion space, into and out of igniting relationship to the dis-
charge from the fuel nozzle.

In testimony whereof, I have signed this specification.

JOHN GOOD.
